BOWLING ALLEY

Theodore R. Treiber, Chicago, Ill., assignor, by
mesne assignments, to Henry E. Gremp, Chi-
cago, Ill.

Application January 26, 1939, Serial No. 252,849

10 Claims.

(Cl. 273—51)

This invention relates to bowling alleys and has for its principal object to provide a bowling alley which can be easily and cheaply constructed and erected without expensive and elaborate foundations.

A further object of the invention is to provide an improved bowling alley which may be constructed from common and inexpensive materials which may be readily fabricated into units easily handled and readily assembled.

A further object of the invention is to provide a bowling alley in which the surface may be adjusted and leveled from time to time by simple adjustments upon the structure and without any changes in the foundation.

Other objects, advantages and capabilities of the invention will appear from the following description of a preferred embodiment thereof, taken in conjunction with the accompanying drawing, in which:

Figure 1 is a plan view of the full bowling alley, showing a fragment of an adjoining alley;

Fig. 2 is a fragmentary side elevation partly in section taken on the line 2—2 in Fig. 4;

Fig. 3 is a fragmentary side elevation of the bowling alley; and

Fig. 4 is a fragmentary view of the transverse section of the bowling alley taken on the line 4—4 in Fig. 1; and

Fig. 5 is a view of an alternative form of support for the gutters and ball return.

Referring to the drawing, the reference numeral 11 designates the bowling alley bed which runs from left to right and full length of the bowling alley and terminates above the pit 12. The pit 12 lies between the right end of the alley beyond the spots 16 for the pins and the back-stop 13.

Ordinarily two of these bowling alley beds are constructed adjacent each other, and in Fig. 1 a fragment of the second alley bed is shown. Parallel and adjacent to the alley beds 11 and running the full length thereof are the gutters 14 on each side of the alley beds 11. These gutters are intended to receive the balls which, in their passage down the bowling alley, leave the bed.

Adjacent each bed, and mounted between the gutters 14 where two alleys are constructed adjacent each other, is the return ball guide 15 by which balls which have completed their passage over the length of the alley and into the pit 12 are returned to the player.

The features thus far described are found in some form in all bowling alleys. In the bowling

alley shown in the drawing and described in this specification the structure itself is novel.

As seen in Fig. 3, and indicated in dotted lines in Fig. 1, two series of posts 17 are mounted in the ground as a foundation for each bowling alley. Each of these posts is capped by a cap 18, and the posts are so placed that these caps are all at substantially the same height above the ground. Secured to the tops of the caps by lag bolts 20 are a pair of longitudinal beams 19, 10 which extend the full length of the bowling alley bed and may be formed in convenient lengths for facility in handling as indicated by the joint 19a where adjoining sections meet. The longitudinal beams 19 may be in the form of angle iron rails. 15

Mounted above the beams 19 are longitudinal rails 21 running the full length of the alley bed 11. These rails are also formed of angle iron and, as indicated by the joint 21a, may also be made up in convenient lengths. The joints 21a 20 are preferably located intermediate the joints 19a.

The rails 21 are fastened to the beams 19 at intervals by the bolts 22 by which the respective bases of the angle iron members are adjustably secured together, and by the bolts 23. The bolts 23 pass through holes in the beams and slots in the rails and thus permit the rails to be raised and lowered by the bolts 22, and to be secured to the beams 19 at various levels. The rails 21 can by these simple adjustments be made perfectly 30 level throughout the full length of the alley bed 11.

Secured to the rails 21 are a series of cross braces 24, also preferably made of angle iron. These cross braces project from the base of each of the rails 21, and where two alleys are constructed adjacent each other, reach from the rail 21 upon the far side of one alley to the rail 21 on the near side of the adjoining alley. Where only a single alley is constructed the braces 24 are supported by simple brackets 24a reaching from the longitudinal beams 19 to the end of each brace 24 as shown in Fig. 5. 35

The cross braces 24 support the perpendicular pillars 28 and 29, upon which are mounted the gutters 14 and ball return guide 15, both constructed of lengths of sheet iron troughs with edges rolled. The lengths of trough are secured together by flanges 30 bent from the ends of the troughs to form continuous gutters running the full length of the alley bed 11. Within each gutter and ball return guide is a wooden channel 31 to form tracks upon which the balls may roll. These channels 31 are also constructed in convenient lengths, joined to form continuous 50 55

channels running the full length of the alley bed.

Supported by the upper edges of the rails 21 are a continuous series of transverse bed plates 25, extending across the full width of the alley bed 11. These bed plates 25 are comparatively narrow and are laid snugly against each other to form an unbroken and substantially solid bed. The bottom of each bed plate is grooved 32 near each end of the plate so that the plate may receive the upper edge of the rail 21 and be thus accurately positioned and locked against dislocation.

In Fig. 4 the bed plate 25 is shown in section as constructed from concrete reinforced by the rods 26 running in different directions through the concrete mass. The plates may also be suitably constructed of other materials such as laminated wood blocks and heavy metal stampings.

20 The bed formed by the transverse bed plates 25 is covered with one or more layers 27 of suitable cementitious composition which will adhere to the bed plates 25 and can be finished to a smooth hard level surface.

25 The bowling alley herein described can be readily erected from the units referred to. Because of the type of construction, a level playing surface can be produced in any place and if any portion of the structure sags or becomes misaligned, simple adjustments will readily restore the structure.

The bowling alley is erected by driving or placing the posts 17 in holes in the ground with their caps 18 substantially level. The beams 19 are 35 then secured to the caps, and the rails 21, with attached cross braces 24, secured to the beams. The rails can then be leveled by the adjusting screws 22 and locked in level position by the bolts 23, or the bed plates 25 first laid in position and the entire bed leveled by adjustment of the 40 adjusting screws 22. The surface 27 can then be applied and finished. Thereupon the gutters 14 and ball return guide 15 can be mounted and the alley is ready for service.

45 If it is desired to remove the bowling alley from one location to another it is only necessary to disassemble the structure. Only the playing surface will be fractured and this can be readily replaced after the bowling alley is again erected.

50 Although the invention has been disclosed in connection with the specific details of a preferred embodiment thereof, it must be understood that such details are not intended to be limitative of the invention except insofar as set forth in the accompanying claims.

55 Having thus described my invention, what I claim is:

1. In a bowling alley structure, the combination of spaced-apart rail means comprising angle beams supported in end to end relationship, floor 60 means forming an alley floor supported by said spaced-apart rail means at the opposed edges of said floor means, said floor means comprising concrete slab means having interfitting relationship with said angle beams at the opposite edges of said floor means to prevent lateral displacement of the floor means with respect to said rail means, and a surfacing layer, comprising a cementitious mastic, covering the upper surface of 65 said floor means.

70 2. In a bowling alley structure, the combination of spaced-apart rail means comprising angle beams supported in end to end relationship, floor means forming an alley floor supported by said spaced-apart rail means at the opposed edges of 75

said floor means, said floor means comprising concrete slab means having interfitting relationship with said angle beams at the opposite edges of said floor means to prevent lateral displacement of the concrete slab means with respect to 5 said rail means, reinforcing means for said concrete slab means extending substantially between the opposite sides of the floor, and a surfacing layer, comprising a cementitious mastic, covering the upper surface of said concrete slab means. 10

3. In a bowling alley structure, the combination of spaced-apart rail means comprising angle beams in end to end relationship, floor means forming an alley floor supported by said rail means at the opposed edges of said floor means, 15 said angle beams having interfitting relationship with said floor means to prevent lateral displacement of the floor means with respect to the rail means, means forming gutters extending at the opposed edges of said floor means, and means for 20 supporting said gutters on said rail means.

4. In a bowling alley structure comprising adjacent alleys, each comprising spaced-apart rails and floor means supported by said rails at the opposed edges of said floor means, gutter support 25 means carried by and between the adjoining rails of the adjacent alleys, and means forming gutters on said support means, including an edge gutter extending along each of the facing edges of the floors of the adjacent alleys. 30

5. In a bowling alley structure comprising adjacent alleys, each comprising spaced-apart rails and floor means supported by said rails at the opposed edges of said floor means, gutter support means carried by and between the adjoining rails 35 of the adjacent alleys, means forming gutters on said support means, including an edge gutter extending along each of the facing edges of the floors of the adjacent alleys, and a ball return gutter on said support means in position extending between said edge gutters. 40

6. In a bowling alley structure comprising adjacent alleys, each comprising spaced-apart rails and floor means supported by said rails at the opposed edges of said floor means, gutter support 45 means carried by and between the adjoining rails of the adjacent alleys, means forming edge gutters on said support means along each of the facing edges of the adjacent alleys, means forming a ball return alley, and means supporting the ball 50 return alley on said support means in position between said edge gutters and at a different elevation.

7. In a bowling alley structure comprising adjacent alleys, each comprising spaced-apart rails and floor means supported by said rails at the opposed edges of said floor means, gutter support means carried by and between the adjoining rails of the adjacent alleys, means forming edge gutters on said support means along each of the facing edges of the adjacent alleys, means forming a ball return alley, and means supporting the ball 60 return alley on said support means in position between said edge gutters, the facing edges of said edge gutters being separated by a distance 65 less than the width of the return gutter, the return and edge gutters being disposed at different elevations and in relative position such that their vertical projections are in overlapping relationship. 70

8. In a bowling alley structure, the combination of spaced-apart rail means comprising angle beams in end to end relationship, floor means forming an alley floor supported by said rail means at the opposed edges of said floor means. 75

- said angle beams having interfitting relationship with said floor means to prevent lateral displacement of the floor means with respect to the rail means, gutter means extending along the edge of
- 5 said floor means and supported on said rail means, said gutter means comprising sheet metal channels, and means forming a pair of spaced-apart, upstanding ribs on the bottom of said metal channels to provide ball tracks therein.
- 10 9. In a bowling alley structure, the combination of spaced-apart rail means comprising angle beams in end to end relationship, floor means forming an alley floor supported by said rail means at the opposed edges of said floor means,
- 15 said angle beams having interfitting relationship with said floor means to prevent lateral displacement of the floor means with respect to the rail means, means forming gutters extending at the opposed edges of said floor means, means for supporting said gutters on said rail means, and
- 20 means for leveling said floor means, comprising adjusting devices at intervals along said rail

means and operable to level the floor and gutter means by adjusting the elevation of the rail means on which the floor and gutter means are both carried.

10. In a bowling alley structure, the combination of spaced-apart rail means comprising angle beams supported in end to end relationship, floor means forming an alley floor supported by said spaced-apart rail means at the opposed edges of said floor means, said floor means comprising 10 concrete slab means having interfitting relationship with said angle beams at the opposite edges of said floor means to prevent lateral displacement of the floor means with respect to said rail means, a surfacing layer, comprising a cementitious mastic, covering the upper surface of said floor means, and means for leveling said floor means, comprising adjusting devices at intervals 15 along said rail means and operable to level the floor.
